Attorney, Agent, or Firm—Harness, Dickey & Pierce, P.L.C.

[57] **CLAIM**

The ornamental design for a bottle, as shown and described.

DESCRIPTION

FIG. 1 is a right side elevation of a bottle showing our new design, the left side elevation is a mirror image thereto; FIG. 2 is a front elevational view thereof; FIG. 3 is a rear elevation thereto; FIG. 4 is a top plan view thereof; and, FIG. 5 is a bottom plan view thereof.

The broken lines in the drawings are for illustrative purposes only and do not form part of the claimed design.
